CLAIM

The ornamental design for a replaceable cover for a camera, as shown and described.

DESCRIPTION

FIG. 1 is a top, front, and side perspective view of a replaceable cover for a camera showing our new design; FIG. 2 is front view thereof.

FIG. 3 is rear view thereof.

FIG. 4 is a side view thereof.

FIG. 5 is a side view thereof.

FIG. 6 is a top view thereof; and,

FIG. 7 is a bottom view thereof.

The broken lines illustrate portions of the replaceable cover for a camera that form no part of the claimed design.
